ADJUSTABLE LABELING MACHINE

Francis A. Craig, Worcester, Mass., assignor to
 Economic Machinery Company, Worcester,
 Mass., a corporation of Massachusetts

Application July 5, 1941, Serial No. 401,249

1 Claim. (Cl. 216—55)

The present invention relates to labeling machines, and particularly to those of the type wherein each label is transferred from the supply stack to a reciprocating carrier, which first subjects the label to gumming and then deposits it on the bottle or other article to be labeled.

In such a machine, the label magazine or supply stack holder must register the labels accurately with the path of travel of the transfer device, and the label carrier in turn must register in label-receiving position with the path of said transfer device, and subsequently, in label-depositing position with the desired label-receiving area of the bottle or other article. Heretofore, these registration requirements have been a serious handicap on the range of adaptability of such machines to labels and bottles of materially different sizes and shapes, because of the need for substantial centralization of the label, on both the transfer device and the carrier.

My invention overcomes these difficulties by the provision of special constructions for the label holder and the label carrier, by which these devices, separately and conjointly, can be adjusted, to adapt the machine to a wide range of label dimensions and shapes, and to a wide range of label positions on the bottles or other articles.

In the label holder of my invention, the various adjustments to different sizes and shapes of labels are achieved in such a manner that the center line of the stack of labels in said holder will always remain in substantially the same position, relative to the other elements of the labeling machine, thus insuring the proper functioning of those elements, regardless of the size and shape of any particular label that is being applied.

Other and further objects and advantages of the invention will hereinafter more fully appear from the following detailed description taken in connection with the accompanying drawings, in which—

Fig. 1 is a fragmentary front elevation of a machine embodying the invention.

Fig. 2 is a front view on a larger scale of the label carrier and its supporting member.

Fig. 3 is a top plan view of said supporting member.

Fig. 4 is a fragmentary side elevation showing the label carrier in a position for depositing a label on an article.

Fig. 5 is a side elevation on a larger scale of the holder for the stack of labels.

Fig. 6 is a perspective view of the label holder as adjusted for a stack of large labels.

Fig. 7 is a front elevation of the label holder as adjusted for a smaller size of label.

Fig. 8 is a schematic side elevation at right angles to Fig. 1 showing the relative positions of the several labeling machine elements.

In the labeling machine fragmentarily shown in Fig. 1, there are uprights 1, one of which supports horizontal guide bars 2 for the horizontally reciprocating supporting member 3 of the label carrier 4. Said carrier receives labels one at a time from a picker 5 and by its said movement carries the label over a roller 24 which applies gum to the underside of the label; thereafter, said carrier deposits the label on an article A. This article, which in the arrangement shown, is a bottle, is supported by a vertically movable bottle rest 6. The arrangement of the parts of the machine correspond in general to the machine disclosed in the copending Holm application, Serial No. 285,306, filed July 19, 1939.

The label supply shown by Fig. 1 is a stack 7 of labels held nearly upright, edgewise, by a box or holder to be described in detail hereinafter. The label picker 5 oscillates, in suitably timed relation to the travel of carrier 4, between the full line and broken line positions shown by Fig. 1; in its upper or full line position, said picker 5 engages and seizes by suction the endmost label of stack 7, and by its down swing disposes said label in a substantially horizontal position, in or just below the plane traversed by the under surface of carrier 4; with the arrival of said carrier over the so-positioned label, the suction on the picker 5 is released, and the suction on the carrier is applied, thereby transferring the label from the picker to the under surface of the carrier.

It has been found desirable to have the label carried as close as possible to the forward edge 4a of the carrier 4. As shown in Fig. 3, said carrier has attached to the underside thereof a rubber element 8 corresponding in shape to the shape of the label and positioned adjacent to the forward edge 4a. Passages through this rubber element provide suction connection between the bottom face thereof and the interior of the carrier. With the label engaging element 8 in this position, it will be obvious that regardless of the dimension of the label, the label carrier in advancing into the position of Fig. 4 to deposit the label onto the bottle, will not travel forwardly any farther than is necessary and will leave visible to the operator all of the portion of the bottle above or in front of the label.

For accommodating the label carrier to dif-

ferent sizes of labels, and for adjusting the same so that the label engaging element 8 will always be at the forward edge of said carrier, the supporting member 3 of said carrier has formed therein a longitudinal slot 9 parallel to the bars 22 on which the support is guided so that the position of the carrier, which is held to the support 3 by the bolt 10 extending through the slot, may be adjusted forwardly or rearwardly of its supporting structure.

For interchangeability, to permit the handling of labels of various sizes and shapes, the carrier 4 as here shown is constituted by a suction box 11 to the underside of which is removably connected a plate 12, the latter having secured thereto the rubber label engaging element 8. In this way, whenever a label of different size or shape is to be used in the machine, the plate 12 is readily removed and replaced by a corresponding plate having the proper size and shape of label carrying element mounted thereon.

The label holder is especially adapted for quick adjustment to accommodate labels of various dimensions and shapes and at the same time to keep the label stack so located that the individual labels will be transferred from the stack to the proper position on the underside of the label carrier. Since the bottles or other articles to be labeled are usually substantially centered on the article support, it is obvious that the center line of the stock of labels should always have the same relative position in the machine, regardless of the size or shape of the label. That is, the longitudinal center line of each stack of labels must be kept substantially in the plane represented by the dot-dash line 13 of Figs. 5 and 7. As shown in Figs. 5 to 7 inclusive, the label holder comprises a base member 14 which may if desired be adjustably supported on one of the side frames 1 as shown in Fig. 1. The base member 14 carries opposed upright side plates 15 at opposite sides thereof which are adjustable toward or away from each other by release of the locking screws 16 which secure the plates to the base. The latter is slotted at 17 to receive a suitable guide 15' on the underside of each plate. Each of the plates 15, 15 along its upper edge carries an elongated finger 18, said fingers at their inner ends being inturned, as shown at 19, 19, in opposed relation; thus, with the plates 15, 15 so adjusted that the spacing between fingers 18, 18 is substantially the distance between the upper and lower edges of a label of stack L or L' (Figs. 5, 6 and 7), the finger portions 19, 19 serve to hold such stack upright, by their slight overlap of the endmost label thereof.

Between the two plates 15 is positioned a removable plate 20 constituting the bottom of the label holder, said plate 20 being suitably attached to base 14 as by a screw or bolt 21. The upper surface of this plate 20 carries a pair of spaced elongated fingers 22 parallel with the fingers 18, 18 and contacted by a side edge of each label of the stack L, the inner ends of fingers 22, 22 having upturned portions 19a, 19a that overlap slightly the lower side edge of the endmost label of the stack. The fingers 18 and 22 are the means to support the labels in such a position that the center line of the stack of labels is properly located with respect to the machine so that the labels when delivered one by one to the transfer pad and from the transfer pad to the article to be labeled, will be cen-

trally and properly positioned on the article. That is to say, if relatively large labels, as shown at L, Fig. 5, are to be applied, then the machine is equipped with a plate 20 which is thin enough so that its fingers 22 will support a stack of labels with the center line in the proper position.

If it is desired to use the machine for applying a much smaller label L', Fig. 7, the only adjustments necessary are the closer spacing of 10 the side plates 15 and the replacement of the central removable plate 20 by another similar plate 20' enough thicker than the plate 20 so that the center line of the stack of labels will still be in the same position with respect to the supporting structure. Obviously, a label holder of this type is adapted for the support of labels of irregular shape. Thus, as shown in Fig. 7, the removable plate 20' is built up so that its two fingers 22' carried thereby are in vertically staggered relation to each other to support a stack of labels L', whose side edges are convergent, as shown. The dot-and-dash lines in Fig. 7 show the position of the parts of the label holder when adjusted to the position of Fig. 6.

It will thus be seen that the change-over of 25 the machine from one size and shape of label to a different size and shape of label is a comparatively simple procedure; any difference in the width of the label is taken care of by selecting a plate 20 of the proper thickness, or 30 by changing the effective length of said plate in the holder, by building it up or down as the case may require; any difference in the height of the label is taken care of by in or out adjustments of the plates 15, 15. The label carrier 4 is readily 35 adapted to such a change, merely by replacing its plate 12 with another similar plate carrying an apertured rubber or like label engaging element 8 corresponding in contour to the new size of label, and the entire label carrier 4 as a unit is adjusted longitudinally of the machine, so that the suction element 8 on the underside thereof will be in accurate alignment with the label when the latter is moved by the picker from 40 the stack of labels to a position beneath the carrier 4. Since the article support 6 is also removable and replaceable, the machine can very rapidly be adapted to different sizes and shapes 45 of articles merely by the removal of one article support and the substitution of a different and 50 properly shaped article support or bottle rest.

In the operation of my machine, assuming its parts to have been properly adjusted in the manner above described, each downward movement 55 of picker 5 removes the endmost label from the stack and carries the same, face up, to a substantially horizontal position directly below the path of label carrier 4, at which point said label will be in direct alignment with the bottle to which the label is to be applied, although obviously the label at this time is offset inwardly of the machine from the bottle, as shown by the position of picker 5 in the diagram of Fig. 8. The label carrier 4 then moves into a position directly 60 above the label on the picker, whereupon by release of the picker's suction and application of the carrier's suction, the label is transferred to 65 said carrier and conveyed thereby over suitable gumming mechanism 23 (Fig. 8) which includes a gum roll 24, for the application of adhesive to the underside of the label. The carrier 4 then 70 conveys the label to a position directly above the bottle, as shown in Fig. 4, so that the label may be transferred directly to the bottle in pre-determined relation to the front of the bottle.

It will thus be apparent that the position to which the carrier 4 is adjusted, relative to its supporting member 3, is of major importance in assuring proper location of the label on the carrier and also accurate location of the label subsequently on the bottle.

It may be noted that in the machine shown, a vertically movable pressure pad 25 located above the bottle, is moved downwardly after the label has been applied to the bottle by the carrier, and assures a proper attachment of the entire area of the label to the bottle or other article.

I claim:

5 In a labeling machine of the class described, a label magazine wherein the labels stand substantially upright on edge in stack formation, said magazine having adjustable sides in opposition to the two upright edges of each label in said stack, inturned spurs on said sides in overlapping relation to the endmost label of said stack, the bottom of said magazine being vertically adjustable, to maintain the center line of said stack, for different sizes and shapes of labels at substantially the level defined by the engagement of said spurs with said endmost label.
